UNITED STATES PATENT OFFICE.

JOSEPH BIJUR, OF NEW YORK, N. Y., ASSIGNEE, BY MESNE ASSIGNMENTS, TO BIJUR MOTOR APPLIANCE COMPANY, A CORPORATION OF DELAWARE.

ELECTRICAL APPARATUS FOR AUTOMOBILES AND THE LIKE.

1,362,771.

Specification of Letters Patent. Patented Dec. 21, 1920.

Application filed October 16, 1916. Serial No. 125,844.

To all whom it may concern:

Be it known that I, JOSEPH BIJUR, a citizen of the United States, and a resident of the borough of Manhattan, in the city, 5 county, and State of New York, have invented an Improvement in Electrical Apparatus for Automobiles and the like, of which the following is a specification.

This invention relates to electrical apparatus for automobiles and the like and with regard to certain more specific features to the mounting of a dynamo electric machine and related parts. One of the objects thereof is to provide apparatus of the above type 15 of enhanced simplicity and effectiveness. Another object is to provide practical means in connection with a dynamo electric machine for maintaining it in efficient and dependable action. Another object is to provide a simple, secure and inexpensive mounting for a dynamo electric machine with relation to an internal combustion engine. Another object is to provide a mounting of the above type in which the apparatus 20 is readily assembled or dismounted and is nevertheless rigidly held in assembled condition. Other objects will be in part obvious and in part pointed out hereinafter.

The invention accordingly consists in the 30 features of construction, combinations of elements and arrangement of parts which will be exemplified in the structure hereinafter described and the scope of the application of which will be indicated in the 35 following claims.

In the accompanying drawings in which is shown one of various possible embodiments of this invention,

Figure 1 is a plan view partially in section showing the mounting of electrical apparatus on an automobile engine;

Fig. 2 is an elevation partially sectional of a dynamo mounted in position;

Fig. 3 is a sectional view along the line 45 3—3 of Fig. 2;

Fig. 4 is an end view of parts shown in Fig. 2.

Similar reference characters refer to similar parts throughout the several views of 50 the drawings.

Referring now to Fig. 1 of the drawings, there is shown at 10 an internal combustion engine preferably of the automobile type, on the crank shaft of which is fixed a

sprocket wheel 11. The engine casing 12 is 55 so formed as to inclose the moving parts and is provided with lateral extensions or legs 13 and 14.

The engine leg 13 incloses the flywheel 15 and the latter is provided with a gear 16 60 by which the engine is started as from the electric motor 17. The latter is mounted on the engine leg by means of a socket 18, and the gear 19 on its armature shaft may be moved into and out of mesh with the gear 65 16 on the flywheel by any desired means. The details of this construction are not here shown as they form in themselves no part of the present invention.

Extending outwardly into the engine leg 70 14 is a sprocket chain 20 which passes over and drives a small sprocket wheel 21 inside the leg but on the armature shaft of a dynamo or generator 22.

The generator 22 may be of any desired 75 form but preferably has a lateral inclosure or yoke 38 generally round in cross section. The driven end of this generator fits within an annular ring or socket 23 on a support 24 formed as indicated in Figs. 2 and 3 of 80 85 the drawings. The end plate 25 of this support with which the socket member is preferably cast integral, is movably mounted against the outside surface of the engine leg 14, and the armature shaft passes 90 through the adjacent wall of this portion of the engine casing or leg and has fixed thereon a sprocket wheel 21. The bearing for this armature shaft 26 is supported in a box 27 formed on the member 24 which 95 also extends through the engine leg, a suitable opening 28 being provided to permit movement of the generator with respect to the portion of the engine casing against which it tightly fits, and to allow sprocket 95 wheel 21 to pass therethrough when the generator is removed. It is to be understood that the engine casing ordinarily contains oil which is splashed about and thoroughly lubricates all parts therein. In this 100 manner, the sprocket wheels with the sprocket chain are kept drenched with oil and in the best running condition, and moreover, the oil works into the bearing of the armature shaft 26 and also maintains that 105 bearing thoroughly lubricated. A drainage passage 29 leads from the end of this bearing and terminates inside the engine leg in

order to return to the engine casing any excess of lubricant creeping along the armature shaft.

The supporting member 24 forms an outwardly extending portion or flange about the socket 23 whereby its points of support are so spaced as to exert a greater leverage and hold the dynamo in position with the utmost security. This flange is preferably provided with a boss 30 at its lowermost part, together with suitable stiffening webs or gussets 31. Through the boss 30 passes a stud 32 with nut 32a by which the support is pivotally mounted on the engine leg. At the upper ends of the support are a pair of elliptical bosses 33 also stiffened by integral webs 34. The parts 33 are provided with elongated openings or slots 35 which are preferably formed on arcs about the pivotal stud 32 as a center. Passing through the slots 35 are studs 36 by which the upper end of the plate 25 is securely gripped and clamped against the engine leg. It will thus be seen that with any desired and proper position of the generator, giving the sprocket chain the proper adjustment, the parts may be reliably held in such position. If, however, it is desired to adjust the position of the generator, it is necessary merely to loosen the nuts on studs 36 and 32 and swing the dynamo either toward or away from the engine into the proper position, whereupon the parts can again be fixed by tightening the nuts. It is to be understood that this movement of the dynamo along the outer face of the engine leg may be attained by other means, although certain advantages are inherent in those above set forth.

Considering the method by which the dynamo is secured within its supporting socket, it is to be noted that its end fits tightly within this socket and rests at its end against the plate 25. Extending through the latter plate in a direction parallel to the armature shaft, are a number of screws 37 which take into the inclosure, yoke or casing 38 of the generator. These screws are preferably countersunk into the plate 25 and extend any desired distance into the dynamo shell. There are also provided radial screws 39 at the top and sides of the socket which pass through suitable bosses 40, preferably cast integral with the socket. These radial screws also extend into the dynamo casing and give an added element of security and strength to its mounting. In the preferred form of the invention, it is thus seen, the end plate member 25 constitutes an end head for the dynamo. In the action of the apparatus, the parts are mounted as indicated in Figs. 1 and 2 of the drawings, and as above described, the moving parts are automatically and thoroughly lubricated from the oil in the engine casing. The adjustment of the chain

is accomplished as above set forth by either swinging or moving the generator toward or away from the engine and clamping it in adjusted position. This movement is readily permitted by the opening 28 shown in Figs. 70 2 and 3 of the drawings. The entire dynamo with sprocket wheel 21 mounted on its shaft is removable as a unit if desired by merely unscrewing the nuts of studs 36 and 32 and drawing the machine with its attached socket off said studs. Though so readily removable, the dynamo is yet securely held in position for the most efficient and effective connection with the engine.

It will thus be seen that there is provided 30 apparatus in which the several objects of this invention are achieved and in which the above and other advantages are attained.

As various possible embodiments might be made of the above invention and as various changes might be made in the embodiment above set forth, it is to be understood that all matter herein set forth or shown in the accompanying drawings is to be interpreted as illustrative and not in a limiting 90 sense.

I claim as my invention:

1. In apparatus of the class described, in combination, an internal combustion engine, a casing extending about a portion of said engine, a dynamo including a lateral inclosure, a supporting member mounted on said casing and embracing one end of said dynamo and thereby supporting the same, power-transmitting wheels, one on said engine and one on said dynamo, and means adapted to vary the position of said supporting member to vary the distance between said wheels.

2. In apparatus of the class described, in combination, an internal combustion engine, a casing extending about a portion of said engine, a dynamo having a yoke, a supporting member mounted on said casing and embracing one end of said yoke and thereby entirely carrying the same, power-transmitting means connecting said dynamo with said engine, said supporting member having formed therein slots extending substantially parallel to the plane of said power-transmitting means, and connecting devices passing through said slots whereby said supporting member may be moved along said casing with respect to said engine.

3. In apparatus of the class described, in combination, an internal combustion engine, a casing extending about a portion of said engine a dynamo including a coaxial inclosure, a supporting member mounted on said casing and embracing one end of said dynamo inclosure and thereby entirely carrying the same, and power-transmitting means connecting said dynamo with said engine, said supporting member being pivotally connected at one point with said cas- 130

- ing and having a slotted connection therewith at another point whereby it may be swung with respect to the casing.
4. In apparatus of the class described, in combination, an internal combustion engine, a fixed member extending about a portion of said engine, a dynamo including a lateral inclosure, a member provided with an annular flange into which one end of said inclosure fits and by which it is entirely supported, flexible power-transmitting means connecting said dynamo with said engine extending parallel to said fixed member, and means mounting said supporting member upon said fixed member constructed and arranged to permit its movement therealong for adjusting the tension of said flexible means.
5. In apparatus of the class described, in combination, an engine casing, a dynamo including a coaxial inclosure, a power-transmitting member, an integral connection extending from said dynamo to said power-transmitting member through said casing and bodily movable therein, and a supporting member into which one end of said inclosure fits and by which it is supported, said supporting member being mounted for varying its position along said casing.
6. In apparatus of the class described, in combination, an engine casing, a dynamo including a lateral inclosure, a power-transmitting member, a connection extending from said dynamo to said power-transmitting member through said casing, and a supporting member into which one end of said inclosure fits and by which it is supported, said supporting member being in face to face engagement with the outer side of said casing and being pivoted at one point to and provided with means whereby it may be swung along said casing and locked in the position in which it is swung.
7. In apparatus of the class described, in combination, an internal combustion engine, a casing about said engine adapted to contain oil, a dynamo without said casing, said dynamo having an integral extension on its shaft, a power-transmitting member within said casing, and attached to said extension, said shaft passing through an opening in said casing larger than said power transmitting member, means within said casing driving said power-transmitting member from said engine, and a device supporting said dynamo upon the outside of said casing, said device being constructed and arranged to permit shifting said shaft parallel to itself.
8. In apparatus of the class described, in combination, an internal combustion engine, a casing about said engine adapted to contain oil, a dynamo without said casing, a power-transmitting member within said cas-
- ing, a rigid connection from said dynamo to said power-transmitting member passing through said casing, means within said casing driving said power-transmitting member from said engine, a device supporting said dynamo upon the outside of said casing, said device being constructed and arranged to permit shifting said shaft parallel to itself, and means whereby excess lubricant is returned from the adjacent bearing of said dynamo.
9. In apparatus of the class described, in combination, a fixed member, a dynamo one side of said fixed member including a coaxial inclosure, a power-transmitting member the other side of said fixed member, rigid means connecting said dynamo and said power-transmitting member passing through said fixed member, and a supporting device provided with a socket into which one end of said inclosure fits and is removably secured and by which said dynamo is supported, said supporting member having a flange extending outwardly beyond said socket and resting against said fixed member, and means extending into elongated slots in said flange for securing the latter to said fixed member in any of a variety of possible positions.
10. In apparatus of the class described, in combination, a vertical fixed member, a dynamo having a yoke, said dynamo being at one side of said fixed member and extending therefrom in a horizontal direction, a power-transmitting member at the other side of said fixed member, a shaft connecting said dynamo and said power-transmitting member passing through said fixed member, a supporting member provided with a socket into which one end of said yoke fits and is removably secured and by which said dynamo is supported, said supporting member having a flange extending outwardly beyond said socket and resting against said fixed member, said flange having elongated slots eccentric of said dynamo, studs upon said fixed member extending into said slots, an internal combustion engine, a portion of which is incased by said fixed member, and flexible driving means co-acting with said power-transmitting member and adapted to drive said dynamo from said engine.
11. A dynamo for motor vehicles comprising in combination a field, an armature, an end head, the shaft of said armature extending through said head and having a power transmitting member mounted thereon, said end head having an embracing socket for said dynamo and an outstanding flange, with elongated slots to permit adjustment.
- In testimony whereof I have signed my name to this specification this tenth day of October, 1916.

JOSEPH BIJUR.
